UNITED STATES PATENT OFFICE

167,582

MOLDED FOOD PRODUCT

Leo Peters, Evanston, Ill.

Application April 8, 1952, Serial No. 19,244

Term of patent 14 years

(Cl. D82—2)

To all whom it may concern:

Be it known that I, Leo Peters, a citizen of the United States, residing at Evanston, county of Cook and State of Illinois, have invented a new, original, and ornamental Design for a Molded Food Product, of which the following is a specification, reference being had to the accompanying drawing, forming a part thereof, in which:

Fig. 1 is a perspective view of a molded food product, showing my new design; Fig. 2 is a top plan view, Fig. 3 is a side elevational view, and Fig. 4 is a bottom plan view thereof.

I claim:

The ornamental design for a molded food product, as shown.

LEO PETERS.
